(57) CLAIM

The ornamental design for the placard holder for jewelry display, as shown and described.

DESCRIPTION

FIG. 1 is a top, left perspective view of a placard holder for jewelry display, the slotted ring case shown in broken lines for illustrative purposes only and forms no part of the claimed design;

FIG. 2 is a left, front perspective view thereof;

FIG. 3 is a right side elevational view thereof;

FIG. 4 is a rear elevational view thereof;

FIG. 5 is a left, front perspective view of a second embodiment of FIG. 1;

FIG. 6 is a right side elevational view of FIG. 5;

FIG. 7 is a rear elevational view of FIG. 5;

FIG. 8 is a top, left perspective view of a third embodiment of FIG. 1, the tab ring holder shown in broken lines for illustrative purposes only and forms no part of the claimed design;

FIG. 9 is a left perspective view of FIG. 8;

FIG. 10 is a right side elevational view thereof; and,

FIG. 11 is a rear elevational view thereof.
